PORTABLE HAND LAMP

Charles S. McGill, Valparaiso, Ind., assignor to
 McGill Manufacturing Company, Valparaiso,
 Ind., a corporation of Indiana

Application October 12, 1931, Serial No. 568,256

2 Claims. (Cl. 240—54)

My invention relates in general to portable hand lamps with a guard and reflector in connection therewith, and in particular to a means for relatively adjusting the lamp or reflector for 5 centering the lamp in the reflector.

Portable hand lamps of the same general class as my invention have heretofore been designed to employ therein incandescent lamps of various sizes but the reflector and wire guard remained 10 in the same position on the lamp regardless of what size bulb was used. Under these circumstances it was impossible for each of the various size bulbs, or perhaps anyone of them to lie in the proper focus in the reflector. As a result 15 the efficiency of the lamp was impaired, and shadows in the reflection from the lamp made it difficult to use the lamp under all circumstances. Not only that but the hand lamp presented an undesirable appearance with the bulb 20 out of symmetry with the reflector and guard.

An object of my invention is to provide means for positioning the reflector on the handle of the portable lamp so that the incandescent lamp is in the proper focus in said reflector, according 25 to the size incandescent lamps inserted in the socket.

A further object of my invention is to provide such means for positioning the reflector on the handle which is inexpensive to manufacture, certain 30 in operation, and which results in a hand lamp neat in appearance.

Other objects and advantages will appear as the description progresses.

Referring now to the drawing:

35 Fig. 1 is a front elevation of a portable hand lamp embodying my invention in which a small sized incandescent lamp is used.

Fig. 2 is a fragmentary front elevation of the hand lamp of Fig. 1 except that a larger lamp 40 is inserted and the reflector positioned or adjusted accordingly.

Portable hand lamps have found their greatest use under conditions where they will be subjected to very rough treatment, such as in garages, by plumbers in installing and repairing plumbing fixtures, by telephone engineers when working on switchboards and other installations, by electricians and innumerable others where the lamps are knocked about and dropped. This 45 use necessitates a sturdy construction, and a guard and reflector for the lamp which will withstand severe shocks. It is also necessary to provide a construction which may be manufactured at a minimum cost, so that the hand lamp 50 may be retailed as a relatively cheap article.

With the above problems in mind I have designed a lamp sturdy in structure, neat in appearance, with means for adapting the reflector to various size incandescent lamps.

Referring to Fig. 1, of my drawing, I have shown for convenience a 40 watt incandescent lamp 12 screwed into an ordinary socket mounted in handle 13 of a portable lamp. The handle 13 may be constructed of a variety of materials, but I have obtained very satisfactory results with 60 use of resilient rubber. The latter not only serves as a good insulator but may be easily and cheaply molded to the desired shape. It also aids in frictionally retaining the guard and reflector. A guard (Fig. 1) with wires broken off 65 at the top and bottom as shown, so that the position of the bulb 12 in relation to the reflector may be more easily seen tapers down to a bi-part assembling and retaining ring 18. The guard is hingedly connected to the reflector at 70 its top 19, and secured to the handle by means of screws 21 and 22 through lugs on both portions of the bi-part retaining ring.

In order that the reflector may be positioned 75 on the handle to bring the electric lamp in the proper focus I provide a plurality of grooves 26 and 27 in the handle 13 in one of which the lower portion 20 of the guard and the channel 28 formed therein will fit. There is a corresponding member 29 on the reflector 17 (Fig. 2). This also has 80 lugs 31 and 32 threaded to receive screws 21 and 22. This construction is shown more clearly in Fig. 2 where the guard is entirely removed.

When, for example, it is desired to employ a 40 watt lamp the screws 21 and 22 are loosened, the 85 guard and reflector removed, and the lamp screwed into the socket. The lower portion of the guard and that of the reflector is fitted into groove 26 with channel 28 of the guard and channel 33 of the reflector resting against bead 34. With the 90 screws 21 and 22 tightened into the lugs on the guard and reflector, a very secure and certain fit is obtained on the handle of the lamp.

The guard and reflector are prevented from 95 moving either up or down by the peculiar construction of the lower portion of each, resting against the abutment 35 and bead 34 on the groove 26. Thus the lamp will survive very rough handling with the electric lamp always in focus 100 throwing a perfect beam of light upon the work which it is illuminating.

If, for example, it is desired to use a 60 watt lamp, the guard and reflector may be fitted into 105 groove 27 (Fig. 2) in the same manner as described in connection with the 40 watt lamp, thus 110

bringing the larger lamp in focus by the predetermined spacing of the groove 27 on the handle. Inasmuch as the electric lamps used today are of standard shape and dimensions for various out-
5 puts it is possible to accurately determine the spacing of the grooves on the handle, and any user will be able to fit standard electric lamps into the portable hand lamp of my invention.

Although I have described my invention in con-
10 junction with portable hand lamps using either a 40 or 60 watt electric lamp, and have shown and described the invention as adapted to only two adjustments for size of lamp, I do not restrict my invention to this alone, but aim to cover all that
15 which comes within the spirit and scope of the appended claims.

What I claim is new and desire to protect by United States Letters Patent is:—

1. In a portable hand lamp, a handle having a
20 socket secured therein adapted for receiving lamps of different sizes, a reflector and guard hingedly connected together tapering to a corresponding bi-part clamping ring neck narrowing into a semi-annular inwardly projecting bead
25

and a semi-annular clamping ring adjacent thereto, said ring having outwardly extending ears at each end thereof, said handle having a plurality of annular grooves each having flanges on each side of the groove and adapted to receive said bead and ring, with the bead abutting one of the flanges and the bottom of the ring abutting the other flange; and screws extending through the outwardly extending ears to clamp the bi-part neck in one of said grooves according to the size lamp in the socket whereby the lamp is rigidly positioned in focus with respect to the reflector.

2. In a portable hand lamp, a handle, a socket held stationary therein and adapted for receiving lamps of different sizes, a reflector, and a guard hingedly attached thereto, said reflector and guard having a bi-part clamping portion including an inwardly extending bead and a clamping ring adjacent thereto, a plurality of grooves in the handle and means for selectively securing said clamping portion in a groove whereby the reflector is supported in focus with a lamp in the socket.
